LEWIS M. VAN SICKLE, OF WOODBRIDGE, NEW JERSEY.

Letters Patent No. 78,843, dated May 26, 1868.

IMPROVED BRICK-MACHINE.

The Schedule referred to in these Letters Patent and making part of the same.

TO ALL WHOM IT MAY CONCERN:

Be it known that I, LEWIS M. VAN SICKLE, of Woodbridge, in the county of Middlesex, and State of New Jersey, have invented a new and improved Brick-Machine; and I do hereby declare that the following is a full, clear, and exact description thereof, which will enable those skilled in the art to make and use the same, reference being had to the accompanying drawings forming part of this specification.

This invention relates to a new and improved machine for moulding and pressing bricks, tile, &c., &c., and it consists in a new and improved construction of the scrapers of the mud-mill, whereby the scrapers are rendered less liable to break than those of ordinary construction.

The invention also consists in a peculiar mechanism for moulding, pressing, and discharging the bricks, as hereinafter fully shown and described, whereby said work may be rapidly performed, and in a perfect manner.

In the accompanying sheet of drawings—

Figure 1 is a side view of my invention, partly in section.

Figure 2, a bottom view of the same.

Figure 3, a detached view of the scrapers pertaining to the mud-mill.

Similar letters of reference indicate corresponding parts

A represents a rectangular box, built within a suitable framing, B, and having a vertical shaft, C, fitted centrally in it.

On the upper end of said shaft there is a sweep, D, to which a horse is attached for rotating the shaft.

This shaft is provided as usual with lateral arms or blades, (not represented,) for tempering the clay, and on the lower part of said shaft, just above the bottom, a, of the press-box, there is fitted a scraper, E, which may be of cast iron, and is composed of a hub, b, having four curved arms, c, the convex sides of which are the face sides, and act upon the clay, and have flanges d to give a broad surface, so as to press or force the same through apertures d, at two opposite sides of the box A, into press-boxes e e.

These press-boxes are each provided with a grating, f, at its bottom, and these gratings are formed into pendent plates g, which constitute the moulds, the front ends and bottoms of the moulds being open.

In each press-box e, a plunger, F, is fitted, and allowed to work freely up and down.

These plungers are each connected, by uprights h, to a horizontal bar, i, the ends of which pass through oblong vertical slots j, in the corner-posts k of the framing B, (see fig. 1,) and the ends of these bars i are connected by links l to the ends of a bar, F', at each side of the framing B, said bars being pivoted centrally to the framing, and each bar provided with central pendent bar, G, the lower ends of the bars G being fitted in a sliding frame, H, underneath the box A, said frame having a reciprocating movement given it from the shaft C, by means of a crank, I, at the lower end of said shaft, working in slotted arms J J, attached to the frame H, (see fig. 2.)

By this means the plungers F are worked up and down.

The reciprocating frame H has dischargers or bars m attached to its ends in line with the moulds or spaces between the pendent plates g, and directly in front of each press-box e there is a rising and falling gate, K.

These gates are attached to vertical bars n n, the upper ends of which are connected by cross-pieces o o, each cross-piece having an upright, p, framed centrally into it, and each upright having a friction-roller, q, in its upper end.

These uprights are alternately depressed, and the gates K forced down by a bevelled surface at the under side of the sweep passing over them, one gate K rising as the other falls, in consequence of the ends of the cross-pieces o o being connected to bars L L, pivoted to opposite sides of the box A.

The parts are so arranged that when a plunger, F, descends, the dischargers m are drawn back from between the pendent plates g, and the gate K in front pressed down, and a bottom-board, M, being underneath the plates, the plunger F, in descending, compresses the clay in the moulds.

When the plunger F has reached its lowest point of descent, the gate K commences to rise, and when fully

up, the dischargers *m* move forward and discharge the bricks from the moulds, and at the same time shove forward the board with them, an empty board placed behind the one with the bricks upon it, being at the same time shoved underneath the moulds.

By this arrangement the bricks will be perfectly moulded, and in a very rapid manner.

The same apparatus will answer for moulding tiles, by employing moulds of a suitable kind.

I claim as new, and desire to secure by Letters Patent—

1. The operating of the plungers *F*, from the vertical shaft *C*, through the medium of the slotted arms *J J*, the reciprocating frame *H*, bars *G F'*, connected with the bars *i*, fitted in the framing *B*, and having the plungers *F* attached to them, substantially in the manner as and for the purpose specified.
2. The gates *K K*, operated as shown, in combination with the dischargers *m*, and the plungers *F*, all arranged so as to be operated from the shaft *C*, in the manner substantially as and for the purpose specified.

L. M. VAN SICKLE.
